METHOD OF FABRICATING SEALED CONTAINERS

John H. Payne, Ballston Spa, N. Y., assignor to
General Electric Company, a corporation of
New York

Application November 20, 1936, Serial No. 111,828

2 Claims. (CL 49—81)

This invention relates to a method of fabricating sealed containers, and more particularly for fabricating liquid contact switches of the general type described and claimed in my copending application, Serial No. 759,527, filed December 28, 1934, of which the present application is a continuation in part.

The switches disclosed in my aforementioned copending application typically comprise a closed vessel consisting of a pair of dished wall members of thin metal separated and insulated from one another by an apertured disk of non-conducting material, a quantity of mercury being provided within the vessel to make and break an electrical circuit between the wall members. It is an object of the present invention to make it possible for such switches to be manufactured economically and under conditions which substantially preclude the possibility of defective fabrication. To this end I have provided a novel apparatus and mode of procedure by which the switch enclosing members may be accurately assembled and joined with a minimum of human supervision.

The invention as a whole may best be understood by reference to the following description taken in connection with the drawing, in which Fig. 1 is a perspective enlarged view showing certain of the switch parts in disassembled relationship; Fig. 2 is a plan view of apparatus suitable for the practice of the present invention; Figs. 3 to 8 are fragmentary views showing progressive steps in the switch assembly; and Figs. 9 and 10 illustrate the filling and sealing of assembled switch containers.

The switch assembly which has been chosen to exemplify the present invention comprises a refractory ceramic disk interposed between hollow metal wall members, the nature and appearance of these elements being well illustrated in Fig. 1. The wall members 10 and 11 each comprise a dished receptacle, typically of about one-half inch inside diameter, having an outwardly projecting flange thereon, such flanges being numbered 13 and 14 respectively. In order to facilitate mounting of the switch each wall member is further provided with a central recess (see recess 16) adapted to act as a socket for a cooperating supporting element.

The size of the dished receptacles is such as to correspond quite closely with that of a circular ceramic body or disk 18 which may be clamped between flanges 13 and 14. An aperture 19 formed in the disk permits a closed electrical circuit to exist during certain positions of the

switch while the imperforate portions of the disk form circuit-interrupting means during other positions. Accurate alinement of the wall enclosing wall members and the ceramic body as well as proper orientation of the opening 19 after assembly are facilitated by means of coating index notches 21 provided in each of the separable parts.

The ceramic disk and the wall members should be of such materials that they are capable of being joined and sealed by a thermoplastic material, for example, a glass. For the ceramic I have successfully employed a refractory oxide mixed with vitrifiable material, a suitable combination being a mixture of about 75 to 85 per cent of magnesia and a complementary proportion of clay. The metal parts may suitably comprise an iron-chromium alloy, a very satisfactory composition being one in which the chromium forms from 26 to 30 per cent of the alloy. As a preliminary to the assembling process it is desirable to clean the metal parts with a grease solvent and to heat the flanges 13 and 14 with a gas flame to degas them and to oxidize the metal slightly.

The assembling of the switch containers is carried out in accordance with my invention by means of a multi-station fabricating apparatus such as is illustrated in Fig. 2. This apparatus comprises, for example, a rotary turntable 24 driven intermittently in such a way that each switch container stops for a definite interval at each of the circumferentially arranged stations a, b, c, d, e, f, g, h, i and j. The operations performed at each of these stations will be set out more completely in the following:

Stations a and b are loading stations at which the supervisory operator may supply and position in proper relationship the principal elements of the switch assembly. These elements may for convenience be spread out on trays 25 and 26 where they are readily accessible to the operator. It will be seen by reference to Fig. 3 that at station a the ceramic disk 18 is positioned between the metal enclosing members 10 and 11, these members being juxtaposed so that the flanges 13 and 14 extend outwardly beyond the disk to form an outwardly open annular channel whose bottom is formed by the outer periphery of the disk. This preliminary assembly is supported on the upper end of a hollow mounting or supporting member which comprises a rounded cap 28 fitting into the depressed face of the switch wall and which has an opening 29 communicating with an orifice 30 in such wall. The cap 28 is

supported by means of a hollow metal tube 32 which is arranged to be vertically movable with respect to a supplemental mounting member 33 concentric therewith. This vertical motion, which may be accomplished by a camming surface 36 operating on the lower extremity of the tube 32, permits the relative elevation of the switch assembly to be modified from station to station in accordance with the requirements of the various operations.

After the metal wall members and the ceramic disk are initially assembled as indicated in Fig. 3 the turntable is rotated to bring this assembly of parts to station *b* where the supporting cap 28 is lowered so that the flange 14 rests on the upper surface of the supplemental mounting member 33. This member, which is suitably of graphite, affords a rest for supporting adjacent the juxtaposed edges of the enclosing members 10 and 11 a premeasured quantity of glass, or other thermoplastic material, which is adapted to join with and seal the various switch parts. A particular material which has been found to be satisfactory for this purpose comprises a commercial lead glass containing about 20 per cent PbO and having a coefficient of thermal expansion of about 90×10^{-7} centimeters per centimeter per degree centigrade. Such material may suitably be provided in the form of a fillet or preferably a preformed closed ring 38 of such size as to be approximately co-extensive with the opening of the channel.

After the switch elements are positioned by the operator in the manner indicated, the loose assembly of separable parts is moved onward to the various succeeding stations of the fabricating apparatus. At stations *c*, *d*, and *e* the parts are heated at a controllable rate, for example, by means of gas burners 39 provided at the stations. In order to bring the various elements up to high temperature by slow degrees so that excessive thermal stresses will be avoided, the flame temperatures of the various burners may be progressively increased as one proceeds from station to station. In addition the individual switch supports may be continuously rotated about their vertical axes to subject all parts to uniform heating, such rotation being accomplished, for example, by a gear 40 secured to the member 33 as indicated in Fig. 5.

By the time the switch assembly as a whole has reached station *e* the ring 38 will have become sufficiently plastic so that it starts to flow under the further application of heat. In order to control the nature of its flow, it is desired to exert internal suction by the application of a partial vacuum to the space enclosed by the switch wall members. This may be accomplished, for example, by connecting the tube 32 to a vacuum chamber adapted to exert the desired degree of suction. Connections for this purpose are illustrated diagrammatically in Fig. 2, in which the conduits 42 shown in dotted outline comprise vacuum ducts running to the various vertical tubular supports 32 from a central chamber 43 which may in turn be connected to a vacuum supply line 44. A combination of stationary ports 45 and movable ports 46 which are controlled by the rotation of the turntable 24 may be provided to secure the application or release of vacuum at any of the various operating stations. The suction thus developed may be communicated to the interior of the switch through the aligned orifices 29 and 30 described in connection with Fig. 3.

As shown in Fig. 6, which illustrates the conditions prevailing at station *g*, the progressive collapse of the ring 38 will permit the thermoplastic material to be drawn into the annular channel defined between the flanges 13 and 14 and the peripheral surface of the ceramic disk 18. If the various materials are properly related as specified in the foregoing description the final result will be to produce a hermetic seal between the thermoplastic material and the metal wall members and at least a liquid-tight seal between the thermoplastic material and the ceramic disk. Under continued heating the softness of the thermoplastic material may be increased to such an extent that its surface tension causes a natural rounding and smoothing of its outwardly exposed surface. This effect is indicated at Fig. 7 and takes place without the necessity for any other forming operation. When this condition is reached, the switch unit is ready to be removed from the assembly apparatus.

While the removal may be accomplished automatically in various ways, I have illustrated in Fig. 8 a particular mode of removal which has proven very satisfactory in actual practice. According to the arrangement shown the completely assembled switch unit is subjected to a blast of air or other gas proceeding from a nozzle 47 positioned adjacent the operating station *j*. It being assumed that the vacuum has been removed from the tube 32 at this station, a relatively slight air pressure is enough to topple the switch unit from its mounting and to cause it to fall on to a suitable removal means illustrated in Fig. 2 as a slide 49, whence it may be conducted to further processing apparatus. In the case illustrated this further apparatus comprises an annealing furnace 51 through which the completed switches are carried on a continuous conveyor, such as a belt 52.

After such annealing and cleaning operations as are required the switches may be filled with a desired amount of mercury or other liquid contact medium. This procedure, which is illustrated in Fig. 9, may suitably be accomplished by means of an injection device 54 having a portion projecting through the opening 30 formed in the wall member 11. Fig. 9 also shows each of the wall members as being provided internally with a small insert 56 of contact metal. These inserts may suitably comprise iron finely coated with platinum and are of course provided before the assembly is begun. Their nature and utility are fully described in an application, Serial No. 47,299 of W. R. Walker, filed October 29, 1935. After the addition of a suitable amount of mercury 59, the switch container may be permanently sealed, for example by welding into the orifice 30 a plug of a difficultly fusible metal such as iron. The sealing operation, which may occur coincidentally with the injection of a protective gas into the switch container, is fully described and claimed in my copending application, Serial No. 76,796, filed April 28, 1936. The nature of the sealing element is indicated generally in Fig. 10, in which it is shown as comprising a small plug 61 welded in place in the orifice 30.

While I have described my invention in connection with specific apparatus and a definite order of procedure, it will be understood that modifications of either may be made by those skilled in the art without departing from the invention. I, therefore, aim in the appended claims to cover all such modifications as fall

within the true spirit and scope of the foregoing disclosure.

What I claim as new and desire to secure by Letters Patent of the United States is:

- 5 1. The method of fabricating a hermetically sealed liquid contact device comprising a pair of flanged metal enclosing members separated by means of an insulating spacer which includes the steps of assembling said members on opposite 10 sides of said spacer with the flanged edges of said members extending outwardly beyond said spacer to form an outwardly open channel whose bottom is closed by the spacer and whose width is positively determined by said spacer, positioning 15 a preformed solid glass member adjacent said flanges, said glass member being coextensive with the opening of said channel after assembly of the said members and spacer, and thereafter heating the said glass member to fusion temperature to fuse the same and producing a partial 20 vacuum within the enclosure formed by said members and spacer to draw said fused glass

member inwardly into contact with the spacer while said spacer maintains the spacing of said members constant.

2. The method of fabricating an electrical device comprising a pair of flanged metal enclosing 5 members desired to be maintained electrically separated during at least certain conditions of use of the device, which method comprises positioning said members on opposite sides of an insulating spacer with said flanges extending 10 outwardly beyond said spacer to provide an outwardly directed channel defined by the said flanges and one surface of the spacer, placing about said channel a preformed conforming member of solid thermoplastic material, heating 15 said material to fusion temperature to fuse the same and simultaneously producing a partial vacuum within the enclosure formed by said members and spacer until the fused thermoplastic material has been drawn into the channel 20 to form a seal between the members.
